INVENTOR :

George W. Bufford,

By Attorneys,

Flaser, Funk & Myers.

UNITED STATES PATENT OFFICE.

GEORGE W. BUFFORD, OF BUFFALO, NEW YORK, ASSIGNOR TO J. H. WILLIAMS & CO.,
OF BROOKLYN, NEW YORK, A CORPORATION OF NEW YORK.

PIPE VISE.

Application filed July 8, 1922. Serial No. 573,702.

To all whom it may concern:

Be it known that I, GEORGE W. BUFFORD, a citizen of the United States of America, residing at Buffalo, in the county of Erie and State of New York, have invented certain new and useful Improvements in Pipe Vises, of which the following is a specification.

The present invention relates to pipe vises and more particularly to such vises employing a chain as one of the clamping elements.

In the devices of this kind now in use, the operating means for fastening and unfastening the clamping chain, is arranged below the bench on which the vise is mounted. This construction necessitates the adjustment of the operating means substantially entirely through the sense of touch and in the course of making the adjustments it frequently happens that the knuckles of the operator become bruised.

According to the present invention I provide operating means in the nature of an adjusting screw extending upwardly through the base or bed plate of the vise and operable from above the bench. The operating means being thus visible to the operator the danger of bruising the knuckles is entirely eliminated. By having the operating means operable from above the bench, the adjustment of the chain can also be more quickly accomplished. The invention also includes other features which will be hereinafter more fully described.

The preferred embodiment of my invention is disclosed in the accompanying drawings wherein;

Figure 1 is a front elevation of the vise showing a pipe clamped therein.

Fig. 2 is a top plan view of the vise with the chain omitted.

Fig. 3 is a side elevation of the vise.

Referring to the drawings, let A indicate the base or bed plate of the device, which as herein shown is formed with openings *a* through which suitable securing means may be passed to fasten the vise to a work bench. To properly position the vise with respect to a bench, the underside of the bed plate is provided with lugs *b* approximately midway its length for engaging the edge of the bench. When mounted, the forward end B of the bed plate A will overhang the bench

for a purpose, presently to be made apparent. 55

The bed plate end portion B is formed with aligned openings C and C' for permitting a clamping chain D to pass therethrough, and with a pair of spaced jaws E flanking said openings. The upper surfaces of the jaws are preferably concave and serrated as indicated by the letter *e*, and adapted for cooperation with the chain D to clamp pipes, rods, or other elements having a curved or cylindrical surface. 65

The chain D which may be of any construction, is preferably formed with its pivot pins projecting at each side of the chain as shown at *d*, to form studs for individual engagement with recesses (not shown) formed in the under side of the bed plate, to adjust the active length of the chain. One end of the chain is connected to a socket F preferably by a pivotal connection and said socket in turn is swivelled on one end of an adjusting screw G extending through a tapped lug C² projecting outwardly from the bed plate end portion B. The swivel connection between the two members may be of any preferred construction and as herein shown is formed by a circumferential groove *g* near the end of member G and a pin *f* extending through the socket F into said groove. The adjusting screw G is operable from above the bed plate of the vise and is formed at its free end with a slidably mounted pin *g'* which provides a suitable handle for operating the adjusting screw. In order that the adjusting screw shall not interfere with the work to be clamped within the vise, it is preferable that said adjusting screw be arranged at an incline or obliquely to the bed plate of the vise as best shown in Fig. 1 of the drawings. 70 75 80 85

To make this construction feasible as a manufacturing proposition, the lug C² is formed at an angle to the bed plate, with the hole in said lug extending perpendicularly therethrough.

In the operation of the device, the work, say a pipe as shown in Fig. 1, is first placed on the jaws E and the chain D then passed around the work and a pivot *d* caused to engage in the recesses provided for said purpose in the underside of the bed plate. The adjusting screw G is then turned until 90 95 100 105 110

the chain tightly clamps the work against the jaws E. To release the work, the adjusting screw is given a few turns in the opposite direction to loosen the chain.

5 While I have shown and described the preferred embodiment of my invention, I do not desire to be limited to the specific construction disclosed, since various changes may be made without departing from the 10 spirit of the invention.

What I claim is:

1. A pipe vise comprising a bed plate having a screw threaded opening therein, an adjusting screw extending through said 15 opening, a chain adapted to extend across the bed plate, one terminal link of said

chain carrying a socket member and the adjusting screw being swiveled to the socket member.

2. A pipe vise comprising a bed plate, an 20 adjusting screw operable from above the bed plate extending therethrough at an obtuse angle to the plane of the bed plate, a chain adapted to extend across the bed plate, one terminal link of said chain carrying a socket member and the lower end of the adjusting screw being swiveled to the 25 socket member.

In witness whereof, I have hereunto signed my name.

GEORGE W. BUFFORD.
